(57) CLAIM

The ornamental design for a teapot with lid, as shown and described.

DESCRIPTION

FIG. 1 is a perspective view of a teapot with lid according to the invention;

FIG. 2 is a perspective view of the teapot with lid shown with the lid removed for ease of illustration;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the lid shown in FIG. 1 removed from the teapot for ease of illustration;

FIG. 10 is a front view thereof;

FIG. 11 is a rear view thereof;

FIG. 12 is a left side view thereof;

FIG. 13 is a right side view thereof;

FIG. 14 is a top view thereof; and,

FIG. 15 is a bottom view thereof.

The broken lines shown in FIG. 8 are for the purpose of illustrating portions of the teapot with lid that form no part of the claimed design.
